UNITED STATES PATENT OFFICE.

MAURICE FERDINAND DE REDON DE COLOMBIER, OF PARIS, FRANCE.

PROPELLED MECHANISM FOR AEROPLANE.

1,031,623.

Specification of Letters Patent.

Patented July 2, 1912.

Application filed March 15, 1911. Serial No. 614,630.

To all whom it may concern:

Be it known that I, MAURICE FERDINAND DE REDON DE COLOMBIER, a citizen of the French Republic, residing at Paris, in France, have invented certain new and useful Improvements in Propelling Mechanism for Aeroplane, of which the following is a specification.

This invention relates to improved mechanism for propelling flying machines or other aeroplane in which the flight is effected by means of moving wings and consists in the novel features of constructions, combinations and arrangements of parts hereinafter fully described and specifically defined in the appended claim.

A practical embodiment of the invention is illustrated in the annexed drawings which shows a flying device in the form of a bird, the action and movement of the wings thereof being similar to those of a bird.

Figure 1 represents, diagrammatically the actuating mechanism of the propelling wings. Fig. 2 is a longitudinal section of a toy in the form of a bird with a wing partially broken away, and Fig. 3 is a plan view of Fig. 2.

The mechanism shown in Fig. 1 is applicable to aeroplane generally, and comprises two parallel shafts m , m^1 driven in opposite directions by bevel gears r , r^1 , with which mesh bevel pinions P , P^1 , mounted on a common shaft O . The shafts m , m^1 are each provided with two cranks B , B^1 , keyed or set at an angle relatively to each other, the extent of angularity depending on the particular application for which the propelling device is intended. The forward cranks B should always be in advance of the cranks B^1 , in the direction of rotation, in order that the connecting rods l coupled to said cranks and actuated thereby will raise or lower the arms a , before the action of the rear connecting rods B^1 acting on the rods l , and connected to other arms a^1 . This causes the raising or lowering of the arms a to take place at different moments to the raising or lowering of the arms a^1 which action produces the warping 50 of the wing surfaces which are mounted on and stretched between the said arms a , a^1 . The wing arms of a , a^1 are mounted on and oscillate about a single shaft c , placed above and centrally between the shafts m , m^1 and 55 the rods l , l^1 are pivotally attached to the

arms a , a^1 at m^2 at equal distances from the axis of the shaft c , to provide for synchronism of the oscillations and equality of the strokes of the wings.

In Figs. 2 and 3 there is represented a toy in the form of a bird, to which the invention is shown as applied. The action of the principal parts is the same as hereinbefore described.

The motor is formed by two twisted rubber bands f , f^1 fixed respectively at one end to hooks f^2 at the ends of the shafts m , m^1 and at the other end to a transverse hooked bar f^3 , situated at the rear end of the stay d forming the lower part of the body of the bird, the upper part being formed by the shaft c . A crank handle or the like n mounted on the shaft O serves to twist or wind up the rubber cords by rotating the shafts m , m^1 through the intermeshing pairs of bevel gears P , P^1 and r , r^1 . Legs e are fixed to the stay d and a covering a^2 of paper, goldbeaterskin, silk, light fabric or other appropriate material is glued to framework of the wings and the body. An elastic cord connects the wings and passes under the stay d and helps to bring back the wings to their lower position.

Q designates the tail or rudder of the device.

The mechanism described and illustrated can be applied for example to a flying machine driven by a powerful motor and in general to aeroplane of all sizes.

What I claim as my invention and desire to secure by Letters Patent of the United States is:—

In an aeroplane, the combination with two wings on longitudinal pivotal axes, two pairs of pivotally mounted arms movable in transverse planes one behind the other at an interval apart and collectively attached two to each wing, two shafts rotatable in opposite directions, cranks on said shafts, one for each arm, set at different relative angles, and connecting rods operatively coupling the cranks to the respective arms.

In witness whereof I have signed this specification in the presence of two witnesses.

MAURICE FERDINAND DE REDON DE COLOMBIER.
